UNITED STATES PATENT OFFICE.

LEVA C. COLLINS, OF PHILADELPHIA, PENNSYLVANIA.

COLLAR-STAY.

No. 818,817.

Specification of Letters Patent.

Patented April 24, 1906.

Application filed April 21, 1905. Serial No. 256,808.

To all whom it may concern:

Be it known that I, LEVA C. COLLINS, a citizen of the United States, residing in the city and county of Philadelphia, State of Pennsylvania, have invented a new and useful Improvement in Collar-Stays, of which the following is a specification.

In ladies' neckwear, and particularly in standing collars and such constructions of the stock type, it is quite desirable to avoid mussing and the distressed appearance of light fabrics when secured about the throat without stiffening means. Efforts have heretofore been made to secure this end by underlying stocks and by stiffening, which must be sewed from side to side or through holes already punched, resulting in injury to the appearance and delay in the fastening by reason of the necessity of searching for the pre-determined apertures and before the needle is passed through them.

The object of my invention is to provide such stiffening means for the collar which is quickly and readily secured in place and which is of suitable material to prevent the wrinkling and wilting common to collars without such stiffening means.

A further object of my invention is to provide bordering edges or terminal stays to be secured to the collar and having upon them attaching means for securing one edge of the collar to the other when it is in position.

A further object of my invention is to improve the appearance and the wearing qualities of the collar.

My invention further consists of novel details of construction, all as will be hereinafter fully set forth.

Figure 1 represents a rear elevation of a collar in extended position, showing several of my stiffening devices in place. Fig. 2 represents an elevation of a preferred form of my stiffening-strip. Fig. 3 represents a view corresponding to Fig. 2, but showing a portion of a covering in place. Fig. 4 represents a longitudinal section corresponding to line xx of Fig. 3 of a completely-covered stay. Fig. 5 represents an elevation of a modification of my device. Fig. 6 represents an elevation of a terminal stay of a type illustrated in Fig. 1.

Similar numerals of reference indicate corresponding parts in the figures.

Referring to the drawings, 1 designates a collar of any suitable material having bordering edges 2, 3, provided with stiffening stays 4, 5 of the type shown in Fig. 6. The

terminal stays consist of narrow strips of any suitable material having longitudinal slits throughout preferably nearly the entire length thereof. In the terminal strips these longitudinal slits are preferably placed at one side of the central line in order to provide a wider part of the strip for the attachment of hooks or eyes 7, 8 or other fastening means by rivets or in any suitable manner, as by sewing through the apertures 9. In the ends of the stays I preferably form apertures 10 in order that longitudinal movement of the stays may be definitely prevented by sewing through these apertures, if desired, and that the cover may be secured at these points. One of the terminal stays is provided with hooks and the other with eyes for the purpose of forming coöperating attaching means for the two ends of the collar in order that it may be speedily and securely fastened about the throat. The longitudinal slits are provided for the purpose of permitting a needle to be passed therethrough in sewing the stays in position. The collar would ordinarily overlap the stays, and this is the preferable form. The illustration in Fig. 1 has been taken in rear elevation to show an underlying collar in order to more clearly illustrate the stays in their position with the hooks and eyes in place. In the intermediate stays I provide the longitudinal slit 6, preferably centraling of the stay. In order to provide a covering for the stays to prevent the material thereof showing through the material of the collar, I have preferred to supply a tubular coating or covering 11, which is preferably in a continuous tube and cut off in lengths somewhat longer than the stay by the length 12, which is turned back upon the end of the stay and which is secured in place at the same time that the cover 11 is maintained tight by means of the hollow rivets 13, which still permit sewing through the aperture 10.

In Fig. 5 I have shown a stay with two longitudinal slits. It will be evident that any number of such slits may be provided and that the slits will be formed centrally at uniform distances from the sides of the strip or in any other preferred form.

In operation I make use of the strips either bare, as shown in Figs. 1 and 2, or covered, as illustrated in Figs. 3 and 4. The strips are readily sewed in place, because the longitudinal slits are throughout their entire length at approximately the same distance from the edge of the slit, which once determined fixes

the location of these slits for passage of the needle sewing them presenting no difficulty. The covered stays are likewise readily secured in place, the sewing passing through the cover 5 and the slit of the same or, where desired, through the edge of the covering alone.

The terminal stays may evidently be furnished with the hooks and eyes or other co-operating attaching means in place as a finished article requiring fastening to the collar only to complete a firm handy means of close and secure attachment throughout the length 10 of the division-line between the ends. The slit for attachment may evidently be located 15 upon either the inner or outer side of the line of attachment between the stay and the hooks, &c.

It will be evident that the stays may be made of aluminium, bone, or any other suitable material, that they may be of any desired dimensions, and that the exterior of the stay or the covering thereof may be decorated or ornamented in any desired manner.

Having thus described my invention, what 20 I claim as new, and desire to secure by Letters Patent, is—

1. In a device of the character described, a strip slitted uninterruptedly throughout substantially its entire length the slit of which is

without the axis of the strip in combination 30 with a tight cover for said strip.

2. In a device of the character described, terminal strips each divided longitudinally by a slit into portions of different width whose edges support each other and coöper- 35 ating fastening devices secured to the strips upon their wider portions.

3. In a device of the character described, a collar, terminal strips therefor, having slits therein, cover upon the strips and fastening 40 devices upon the strips to secure the latter together.

4. In a device of the character described, a strip of uniform thickness, longitudinally slitted throughout substantially its length, 45 and a tight-fitting tubular covering secured to the strip at its ends.

5. In a device of the character described, a single longitudinally-slitted strip integral at its ends, whereby the same is of uniform 50 thickness, a tubular covering closely engaging the strip and means passing through the body of the strip for securing the covering thereto.
